STRIPPER DEVICE FOR FLAT WORK IRONERS

Charles Edwin Hamilton, Sr., Hollywood, Calif., assignor to Edwin Lane, Percy Mendelson, and Charles Mendelson, all of New York, N. Y.

Application April 7, 1933, Serial No. 664,962

(CL 68—9)

3 Claims.

The invention relates to laundry and dry cleaner machinery, and more especially to the so-called flat work ironers of either the chest or cylinder type.

In accordance with the usual practice in the operation of these ironers, a plurality of cloth-covered rolls is journaled for rotation above a steam-heated drum or a chest, and the articles to be ironed are caused to be passed onward from one roll to the next by the use of a series of endless strings or tapes disposed transversely of the rolls.

In prior U. S. Patents Nos. 1,186,640, 1,740,980, 1,860,538 and 1,867,741, flexible stripper fingers, in lieu of the strings or tapes heretofore utilized, are disclosed as associated with the individual rolls for the stripping of the work therefrom. The type of stripping means set forth in these patents is confined to members which are located only on one side of a roll, to wit, the delivery side thereof, or at least do not pass between an ironing roll and the corresponding portion of the heating chest.

The present invention has for its object the provision of a novel stripper device for use in flat work ironing machines and wherein the device not only provides for the proper stripping of the goods from the roll surface but insures the retention of the cover cloth in position on the roll, and prevents the work stripped from the roll from rising unduly in the portion between successive rolls, as well as directing the work to the nip of the next succeeding roll.

A further object of the invention resides in the provision of means for adjusting the height of the goods directing means above the corresponding chest portion.

Still another object of the invention resides in simple and effective means for applying rapidly a plurality of stripping elements in securing the stripping device in position, and for facilitating replacement of a stripping element; also, in simple and effective means whereby the passage simultaneously of a multiplicity of the same between a roll and chest may be effected.

Another object of the invention resides in the arrangement whereby the ends of a stripper element are prevented from curling, both in locating the same in position and when in operation.

In carrying out the invention, there is provided in connection with each of the successive rolls a plurality of narrow and resilient metal bands which are arranged to pass beneath a roll from its feed side to the delivery side, being disposed longitudinally of said roll; and suitable support

means are provided at the opposite sides of the roll for this purpose. The support for the far end of a band on the delivery side of a roll may serve also for the support for the feed side end of a band for the next succeeding roll. Provision is made for uniting and spacing all of the far ends of the various bands prior to passing the same beneath a roll (when the pressure is released thereon) so that no difficulty will be experienced in setting up the stripper device for use. The arrangement is such, moreover, that an end of a band is readily mounted in and withdrawn from the uniting member for the multiplicity of bands; and the mounting of the uniting member as a whole on its support also is readily accomplished, while the support itself is designed to be adjustable vertically with respect to the steam chest.

The nature of the invention, however, will best be understood when described in connection with the accompanying drawings, in which:

Fig. 1 is a fragmentary transverse section through a succession of ironing rolls and associated steam chests, and illustrates the application of the stripper device thereto, and the mounting of the same upon a frame of the ironing machine.

Fig. 2 is a fragmentary longitudinal section of the ironing machine and taken on the line 2—2, Fig. 1 of the drawings, looking in the direction of the arrows.

Fig. 3 is a perspective view of the novel stripper element; and Fig. 4 is a similar view of the uniting and spacing member for positioning the ends of the stripper elements.

Fig. 5 is a fragmentary transverse section illustrating the manner of applying the stripping device to the ironing machine.

Fig. 6 illustrates a modification in the manner of applying the stripping elements to spacer bars therefor.

Referring to the drawings, more particularly Figs. 1 and 2 thereof, 10, 11 and 12 designate a succession of intermediate ironing rolls such as the third, fourth and fifth rolls of an eight-roll ironer and utilized in a flat work ironing machine, for example of the chest type, a said roll being journaled for rotation in the frame 13 above a steam-heated chest 14 and the surface of which immediately beneath the roll is generally concave to secure greater ironing contact. When pressure is relieved from these rolls, a slight space or clearance 15, Fig. 5, of approximately $\frac{1}{8}$ of an inch is provided to admit of the passage therethrough of the multiplicity of stripping elements with

uniting and spacing member, as hereinafter set forth.

A cover cloth 16, usually hair padding, wool padding, or matted padding, is frictionally held on a 5 roll in overlapping relationship to insure retention of the cover on the roll surface. In the use of the novel stripping device hereinafter more fully set forth, this retention of the cover cloth is further insured.

10 In accordance with the invention, a stripping device comprises a plurality of narrow resilient metal bands 20 preferably of relatively low-tempered steel and which are designed to pass beneath a roll and are arranged to be spaced longitudinally along the same substantially throughout its entire length. These bands are of sufficient length to embrace a substantial portion of the roll on its feed side and then to extend on the delivery side of the roll a substantial distance 15 toward the next succeeding roll adjacent the place of departure of the goods from the first-named roll and above the periphery of the associated steam chest. The goods stripped from the roll by the band are prevented by this extending portion from rising unduly and are directed thereby 20 to the nip of the next succeeding roll.

Thus, the portion 21 of a band serves to retain the cover cloth in position on the roll during the period it is most likely to become separated 25 therefrom; the portion 22 to strip the goods from the roll; and the portion 23 to prevent undue rising of the goods, and to direct the same to the nip of the next succeeding roll.

In order to better secure this action of the portion 30 extending into the space between successive rolls, and to insure the breaking down the goods from the band, it is preferred to give a band a more or less permanent set or deformation from a rectilinear path, as by kinking the same at the points 24 along the outer portion of its length. This will tend to break or separate the goods from 35 the stripper and prevent travel along the same which might cause them to fall back and become tangled instead of travelling normally to the nip of the next succeeding roll.

The various resilient elements or metal bands 40 thus provided along a roll are arranged to be supported at their respective inner ends, as by means of a bracket 25 secured to the frame 13; and, similarly, their far ends are positively positioned beyond a roll to an extension 26 of the bracket and a further bracket 27, the brackets 25 being fixed to members 27 extending parallel to the rolls and securing the said brackets to the frame.

45 Various expedients may be utilized for the mounting of the said respective ends of a band; and a convenient means for thus mounting the same is disclosed in Figs. 3 and 4. As shown, the opposite ends of a band are reinforced as by each having secured thereto pins 28 and 29, respectively, and which are arranged substantially at right angles to the length of the band. By materially reducing the temper of the ends of the bands, an end may be wrapped about its rod and then spot-welded thereto. The said pins, in turn, 50 are designed to rest in a channel portion 30 of a uniting and spacing bar 31, preferably of low-tempered steel, said channel being to this end provided at its forward wall with suitable entrance slots 32 designed to pass the corresponding band end, and providing more or less resilient intermediate lips behind which the pins may be snapped.

55 This will serve to unite all of the band ends to

a common holding member which also secures proper spacing of the bands longitudinally; and in installing the stripping device on a roll the bar with its attached band elements is passed through the clearance between the roll and its steam chest, as indicated in Fig. 5 of the drawings. This greatly facilitates the assembly of the stripping device in the ironing machine as it is not necessary to individually pass a band beneath the roll; and this is of similar advantage in the withdrawal or replacement of a band which may readily be dislodged manually from its position in the channel of the said bar.

Furthermore, all this may be accomplished without the necessity of climbing to the top of 15 the ironing machine and without interference of a canopy usually provided above these machines. It is also to be noted that no curling or twisting of a band occurs which would ordinarily take place beneath a roll when the pressure is applied thereto, causing breakage of the band and ruining the cover cloth of the roll.

Other means of securing an end may, of course, be substituted for the means hereinbefore described. For example, reference being had to Fig. 25 6 of the drawings, the opposite ends of a band may be enlarged or otherwise reinforced and perforated to afford attaching eyes 33 and 34 adapted to snap over buttons 35 and 36 projecting from the surfaces of the spacing bars 37 and 38.

When the bands have thus been attached to the respective uniting and spacing bars 31 or 37, 30 38, these bars may conveniently be located on the supports 25 and 27 through studs 39 and 40 adapted to receive keyhole slots 41 and 42 of 35 the bars. The far end of a band is thus positioned positively beyond its roll in the space between successive rolls and at a point in advance of the next succeeding roll; and the extent of its elevation above the corresponding steam chest 40 may be set as desired by making the support or bracket 27 adjustable, through a bolt 43 fitting slot 44 of the bracket portion 26.

With the ends so positioned in their bars, 45 there is no interference between loose ends and no twisting or curling of the relatively thin and narrow metal bands occurs during operation or in the installation or removal of the stripping device. It is desirable to have such bands particularly thin and narrow not only to simplify 50 the installation but also to reduce to a minimum stripper imprints upon the goods passing through the machine, as well as to render the device as compact as possible for transportation.

I claim:

1. A stripper device for flat work ironing machines including a heat chest and a plurality of successive ironing rolls, said device comprising a resilient metal band having an end supported at the feed side of a roll and the band extending 60 therefrom between said roll and the cooperating chest portion to the delivery side of the roll, and means to support the other end of said band beyond said roll and at a point in advance of the next succeeding roll, the band between the roll 65 and its far end having a portion permanently deformed from a rectilinear path whereby breakdown of goods from the band is insured.

2. In a flat work ironing machine including a frame, a heat chest mounted thereon, a plurality of successive ironing rolls rotatably mounted in the frame above the heat chest, and a stripper device including a resilient metal band associated with the surface of a roll and extending from the feed side thereof between said roll and the co- 70 75

operating chest portion to the delivery side of said roll, a supporting bracket at the feed side of the roll, a supporting bracket at the delivery side of the roll and constituting a support for the band of the next succeeding roll, means to secure the feed side end of the first-named band to the said bracket at the feed side of the roll, means to secure the delivery side end of said first-named band to the said bracket at the delivery side of the roll, and means to adjust the supporting bracket for the delivery side end of the band relatively to the frame.

5 3. In a flat work ironing machine including a frame, a heat chest mounted thereon, a plurality of successive ironing rolls rotatably mounted in the frame above the heat chest, and a stripper

device including a plurality of resilient metal bands associated with the surface of a roll and extending from the feed side thereof between said roll and the cooperating chest portion to the delivery side of said roll, a common support for the bands at the feed side of a roll, a common support for the bands at the delivery side of a roll and constituting a support for the bands of the next succeeding roll, a bar having key slots and provided with a channel portion having vertical entrance slots, studs extending from the supporting brackets to receive the key slots of the bar, and pins secured to the respective ends of the bands adapted to rest in the channel portion of the bar.
